Primary Examiner — Sharon S Oum(74) *Attorney, Agent, or Firm* — MLO, a professional corp.(57) **CLAIM**

The ornamental design for a fan, as shown and described.

DESCRIPTION

FIG. 1 is a front perspective view of a fan showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear perspective view of FIG. 1.

The dashed broken lines depict portions of a fan in which the design is embodied that form no part of the claimed design.
